AIRPLANE SEAT FOR A FLIGHT ENGINEER OR THE LIKE

Frank J. Del Giudice, Seattle, Wash., assignor to Boeing
Airplane Company, a corporation of Delaware

Application April 5, 1956, Serial No. 40,926

Term of patent 14 years

(Cl. D15—1)

Fig. 2.

Fig. 1.

Fig. 4.

Fig. 3.

Figure 1 is a perspective view of the front and right side of an airplane seat for a flight engineer or the like showing my new design,

Figure 2 is a perspective view of the back and left side of the seat shown in Figure 1,

Figure 3 is a side elevational view of an airplane seat for a flight engineer or the like taken from the left as shown in Figure 1 and,

Figure 4 is a front elevational view of the seat shown in Figure 1.

I claim:

The ornamental design for an airplane seat for a flight engineer or the like, substantially as shown.
